UNITED STATES PATENT OFFICE.

JAMES J. LODGE, OF NEW YORK, N. Y.

ELECTRICAL PROTECTIVE DEVICE.

1,399,502.

Specification of Letters Patent.

Patented Dec. 6, 1921.

Application filed December 18, 1918. Serial No. 267,225.

To all whom it may concern:

Be it known that I, JAMES J. LODGE, a subject of the King of Great Britain, residing at borough of Manhattan, city, county, and State of New York, have invented new and useful Improvements in Electrical Protective Devices, of which the following is a specification.

This invention relates to protective devices for electrical apparatus.

In the use of standard lamp or wall sockets, and similar contact devices it is within the power of any guest or other party in a hotel or similar abode to replace any lamp by a lamp of higher electrical wattage or to employ an electrical iron, heater or the like, notwithstanding the desires of the party in control to the contrary.

An object of this invention is to provide means for precluding the insertion within any standard or similar electrical contact device, such as electrical lamp or wall sockets, or the like, of lamps, plugs or like electrical attachment or consumption device undesired by the party in control of such electrical sockets or other contact means. Thus, in accordance with my invention, in hotel and similar uses, the party in control may provide for lamps or other consumption of his choosing to be used with the lamp sockets or other contact means, and accordingly regulate the use of electrical irons, heaters, stoves, and the like, of his own choosing.

In accordance with the most preferred forms of my invention, means are provided to be inserted within any standard or similar socket or other electrical contact device and the lamp or other attachment or consumption device desired by the party in control to be used in such socket reduced in diameter or otherwise modified or special lamp or other electrical apparatus provided, enabling such desired lamp or other apparatus to be readily positioned in operative relation with the contacts of the socket or other contact means but precluding the use of any standard lamp or standard plug.

Further features and objects of the invention will be more fully understood from the following description and the accompanying drawings, in which—

Figure 1 shows in central section a standard socket having my insert means positioned therein;

Fig. 2 is a sectional elevation of my insert means removed from the socket;

Fig. 3 is a face view of a disk, optionally used as a part of my insert means;

Fig. 4 is a side elevation of a plug adapted to coöperate with my insert means to be positioned within the socket in operative relation with the electrical contacts thereof; and

Fig. 5 is a side elevation of an electrical lamp adapted in coöperation with my insert means to be inserted within the electrical socket.

Referring to the drawings, the socket 1 is shown as of usual standard construction comprising the inner threaded metal contact 70 or shell 2 adapted to be connected to one line of the circuit and the rearwardly disposed button 3 adapted to be connected to the opposite line of the circuit.

My insert means comprises the sleeve portion 4 which may be threaded, say for example two and one-half or three threads and accordingly of approximately one-half of the length of the metal contact shell 2. Such sleeve portion 4 may be of insulating material, or may be of conducting material, in which latter instance, I provide the insulating member 5, such as a disk of insulating material having the substantially central opening 6.

If desired, such disk 5 may be secured to the rearward portion of the sleeve 4, as by providing the sleeve 4 with the crimped flange 4^a and affixing such disk 5 to such flange 4^a by glue or cement or the like, as indicated in Fig. 1. In such construction, the sleeve 4 may be of metal, similar to the metal shell 2 of the socket, but of slightly reduced inner and outer diameters. In use, the disk 5 is positioned rearwardly of the sleeve 4 within the shell 2 of the socket and thus practically hidden from view, particularly when the sleeve 4 is made of the same metal as the shell 2.

The attachment or consumption device 100 desired to be used in the socket, as thus provided with my insert means, is provided with threads of its contact reduced or otherwise modified in accordance with the insert means, say from two and one-half threads, 105 whereby the contact of such attachment or consumption device is received within my insert means and electrical connection effected. Thus, the standard plugs, lamps and the like may be utilized with my invention 110 by pressing in the required number of threads. Special plugs or lamps or the like,

initially provided with the reduced or modified contact, may also be utilized with my invention.

In Fig. 4, I have indicated the plug 7 having its foremost threads 9 reduced in diameter, relative to the remaining threads 10. In Fig. 5, I have shown a lamp 8 having a similar reduced threaded portion 9 and the standard threaded portion 10.

10. It will be apparent that my insert sleeve or other hollow member 4 need not be threaded, nor necessarily of electrically conductive material. It will also be apparent that my insert means may be removably positioned within the socket or other contact means or fixed therein, by means of solder, or equivalent.

20. The control afforded by my invention enables different forms, *i. e.*, different diameters of insert means to be provided respectively for lamps and plugs, and thus restrict certain sockets for lamp use and certain other sockets for use with plugs of curlers, stoves and the like, respectively. Such regulated control is readily carried out by reason of the relatively small variations in dimensions effective in permitting the desired consumption device to be inserted but precluding the insertion of any undesired consumption device.

30. Whereas I have described my invention by reference to specific forms thereof, it will be understood that many changes and modifications may be made without departing from the spirit of the invention as defined by the appended claims.

I claim:

1. The combination with an electrical socket provided with a uniform circular hollow member of electrically conducting material serving as one contact and of predetermined depth for receiving the base of an electrical lamp or plug, said socket having its other contact insulatingly mounted interiorly of said hollow member of protecting means comprising a hollow element having an outer diameter less than the said uniform diameter of said recess and positioned within said recess, said protecting device 40 when in position in said recess freely exposing the contacts of said socket for electrical connection, said hollow element having a length appreciably less than said predetermined depth of said recess, whereby 45 upon insertion of the lamp or the plug the base of the lamp or the plug extends through said hollow member to afford electrical connection between the contacts of the socket respectively with the contacts of said base 50 respectively.

2. The combination with an electrical socket having a receiving opening of a predetermined depth and a threaded contact disposed within said opening and another contact disposed rearwardly within said open-

ing, of a hollow member in electrical connection with said threaded contact and insulated from said another contact and disposed within said receiving opening, said hollow member having a length appreciably less than said predetermined depth, said hollow member being open at its outward and inward ends to provide free electrical access to said another contact.

3. The combination with an electrical 75 socket having a receiving opening of a predetermined depth and a threaded contact disposed within said opening and another contact disposed rearwardly within said opening, of a hollow threaded member in 80 electrical connection with said threaded contact and insulated from said another contact and disposed within said receiving opening, said hollow member having a length appreciably less than said predetermined depth, 85 said hollow member being open at its outward and inward ends to provide free electrical access to said another contact.

4. The combination of an electrical socket comprising a hollow circular shell serving as 90 one contact, a base of insulating material and a second contact mounted on said base and within said shell, of protecting means comprising a hollow circular member positioned within said shell, said hollow member 95 having open ends to provide unobstructed and direct access to said second contact through said hollow member.

5. The combination of an electrical socket comprising a hollow circular shell serving as 100 one contact, a base of insulating material and a second contact mounted on said base and within said shell, of protecting means comprising a perforated hollow circular member positioned within said shell, a member of insulating material, said member of insulating material being perforated to provide direct electrical access to said second contact through said hollow circular member and said member of insulating material.

6. The combination with an electrical socket having a threaded shell serving as one contact and a second contact disposed rearwardly of the opening of said shell, of a threaded hollow member having a length 105 less than the length of said threaded shell and disposed within said shell, a member of insulating material disposed between said threaded member and said second contact but exposing said second contact and a base of an electrical attachment device having its end threads reduced in exterior diameter, whereby upon insertion of such plug within said socket, said reduced threading of said plug extends through said threaded member 115 and said insulating member to establish contact with said threaded shell and said second contact of said socket.

7. The combination with an electrical socket comprising a hollow shell serving as 120

- one contact, a base of insulating material and a second contact mounted on said base, of a hollow circular member constructed to be positioned within said shell, said hollow member having open ends and a base of an electrical device being threaded throughout its outer face serving as a contact and constructed to engage in electrical connection within said shell, said threaded face having
- 5 for a certain portion thereof a threading of a determined diameter and the remaining portion for an appreciable extent being of reduced outer diameter and projecting through said hollow member.
- 10 8. The combination of an electrical socket comprising a circular shell serving as one contact and a second contact disposed at the
- base of said shell, protecting means comprising a hollow circular element constructed to slidably engage said circular shell, said hollow circular element being open at its inward and outward ends, a perforated disk of insulation disposed between the inward end of said hollow circular element and said second contact and a base of an electrical attachment device having its forward portion of relatively less cross section and extending within said hollow circular element and its rearward portion of relatively greater cross section to electrically engage said circular shell.
- 15

In testimony whereof I have signed this specification this 9th day of December 1918.

JAMES J. LODGE.
